Primary Examiner — Cary M Robinson*Assistant Examiner* — Adam C Mager(74) *Attorney, Agent, or Firm* — Polsinelli PC(57) **CLAIM**

The ornamental design for a truck bed rack, as shown and described.

DESCRIPTION

FIG. 1 is a topside perspective view of a truck bed rack showing our new design.

FIG. 2 is a front plan view thereof.

FIG. 3 is a back plan view thereof.

FIG. 4 is a right side view thereof.

FIG. 5 is a left side view thereof.

FIG. 6 is a top plan view thereof; and,

FIG. 7 is a bottom elevation view thereof.

The broken lines shown in the drawings illustrate portions of the truck bed rack and forms no part of the claimed design. The shade lines in the drawings show contour and not surface ornamentation.
